(57) **CLAIM**

The ornamental design for a boom for the distribution of concrete or similar article, as shown and described.

DESCRIPTION

FIG. 1 is a first perspective view of a boom for the distribution of concrete or similar article showing our new design;

FIG. 2 is a second perspective view thereof;

FIG. 3 is a front view of one end thereof;

FIG. 4 is a front view of the other end thereof;

FIG. 5 is a back view of one end thereof;

FIG. 6 is a back view of the other end thereof;

FIG. 7 is the right side view of one end thereof;

FIG. 8 is a right side view of the other end thereof;

FIG. 9 is a left side view of one end thereof; and,

FIG. 10 is a left side view of the other end thereof.

The boom is shown broken away in FIGS. 3 through 10 for convenience of illustration.
